UNITED STATES PATENT OFFICE

JOHANNES KRISTIAN FOLKER, OF CHARLOTTENLUND, AND FREDERIK FERDINAND TRUELSEN, OF COPENHAGEN, DENMARK

SACK INVERTING MACHINE

Application filed August 31, 1931, Serial No. 560,464, and in Germany February 13, 1931.

Sacks or bags are usually manufactured in the following manner: A piece of material is cut of such a size that the sack or bag need only be sewn together along its two edges (the one longitudinal edge and the bottom), the sack or bag being sewn the inside out and being subsequently inverted manually over a suitable buck or the like. However, in wholesale manufacture this method is uneconomical and causes loss of time.

The present invention relates to a machine adapted to invert the sack or bag without any manual operation being required with exception of the placing in the machine of the sack or bag.

The machine according to the present invention operates in the following manner:

The sack placed upon a table of the machine is opened by means of suction from two suction pipes located the one above and the other below the sack. Two grippers in the machine are subsequently introduced into the opened sack so as to stretch the same and on their return movement said grippers will draw the stretched-out sack on to a pivotable turn-over buck in the free end of which an opening is formed. When the sack has been drawn on to said turn-over buck the free end of the latter will swing downwards and will be stopped in this movement at the level of a turn-over fork which is subsequently moved to the bottom of the sack from which position it will press said bottom into the sack through the opening in the end of the turn-over buck so that the sack will now rest outside out on the turn-over fork. The sack is now caught and held by a clamping device, so that it will, on the turn-over fork returning and the turn-over buck swinging upwards, be made free from the turn-over fork by being drawn off the latter and will, as the clamping device simultaneously releases its hold on the sack, drop down into a collector.

A form of execution of the invention is by way of example illustrated in the drawings, where

Fig. 1 shows a sack inverting machine according to the present invention in side view, a few parts being removed so as to clearly show the single members,

Fig. 2 shows the machine in Fig. 1 in top view,

Fig. 3 is a perspective drawing of the turn-over buck and turn-over fork of the machine,

Fig. 4 is a section, at a larger scale, along the line IV—IV in Fig. 2,

Fig. 5 is a section, at a larger scale, through the suction device along the line V—V in Fig. 1,

Figs. 6, 7, 8, 9 and 10 show diagrammatically the relative positions of the sack, the turn-over buck and the turn-over fork at various stages of the inverting operation.

1 indicates a machine frame carrying the several members. 2 is a turn-over buck which consists (Fig. 3) of a frame 3 to the underside of which two side plates 4 are welded and connected at the closed end of said frame 3 to a bridge 5 provided centrally with a resilient flap 6. A square opening is thus formed at the end of the turn-over buck. The one end of the frame 3 is secured to a sleeve 7 which latter is secured to a shaft 8 (Fig. 1). The shaft 8 carries outside the machine frame 1 a long downwardly extending arm 9 secured to the end of said shaft so that a swinging movement of the arm 9 will cause the free end of the turn-over buck to be lifted or lowered. The shaft 8 is journaled in bearings 10 in the frame 1. The swinging movement of the arm 9 is brought about by means of a rod 11 and a lever 12 the arms of which form an obtuse angle. An oscillating movement is imparted to said lever 12 by means of a roller 13 secured thereto and contacting with the circumference of an eccentric cam 14 secured to a tooth wheel 15. Said tooth wheel 15 is operated by a pinion 16 on the machine driving shaft 17 which latter may be driven, for example by a pulley 18 receiving the driving power from a motor, a gear transmission or other suitable source. Instead of using the pulley the driving shaft may receive the power, through a suitable clutch, from an electric motor mounted on the machine frame.

19 indicates a turn-over fork (Fig. 3) and consists of a stem 20 secured at its one end to a slide 21 (Fig. 2) adapted to slide in guides or the like at the top of the frame 1. The stem 20 carries in its free end a cross piece 23

provided with a central recess 24. The stem 20 carries almost centrally two arms 25 on the ends of which two rods 27 actuated by springs 26 are adapted to oscillate. Said rods 27 are S-shaped and are at their free ends provided with rollers 28 which, when the rods are pressed against the stem 20, rest in two semi-circular recesses 29 in the ends of the cross piece 23. During the operation of the machine the rods 27 are pressed against the stem 20 by means of two rollers 30 provided in a bar 31 (Fig. 1) secured to the frame 1.

The slide 21 and thus the turn-over fork are adapted to be reciprocated along the guides 22 of the frame by means of an arm 32 rotatably secured to a mounting 33 on the slide 21 and adapted to oscillate in the machine frame around a pin 34. The reciprocating movement of the arm 32 and thus of the slide 21 is produced by a crank arm 36 driven by a crank 35 keyed to a shaft 37 which latter carries the above mentioned tooth wheel 15. The shaft 37 is journalled in bearings 38 in the frame 1.

At the top of the frame there are provided two inclined guiding lists 39 in which a slide 40 is adapted to move. Said slide 40 is moved by means of an arm 41 provided at its top with a guiding piece 42 having a race 43 in which a pin 45 is adapted to reciprocate, said pin being journalled in a bearing mounted on said slide 40.

The slide 40 has a cross bar (Fig. 2) to which two grippers 46 are secured which are each in the shape of a single-armed lever oscillating around a pin in bearings 47. The said grippers serve to hold the open end of the sack stretched to a suitable degree subsequent to the two parts of the mouth of the sack having been removed from one another by means of the suction to be described later on. When this has taken place the grippers 46 are introduced into the mouth of the sack 45 and the height of said grippers is so adjusted that the sack mouth during the stretching operation will remain large enough to allow it of being drawn on to the turn-over buck. The free ends of the two grippers are forced 50 away from one another by means of two twisting springs located in housings 48 (Fig. 1) on the bearings 47. The grippers are provided with a central outwardly projecting arm having a roller 47a.

55 A reciprocating movement is imparted to the arm 41 and thus to the slide 40 by means of a pull rod 49 the one end of which is rotatably connected to a pin 50 eccentrically disposed on the tooth wheel 15.

60 The one of the guide lists 39 carries a bearing 51 (Fig. 1) for a pin of a bell crank lever 52 the long arm of which carries in its extreme free end an upper suction pipe positioned laterally over the machine and having 65 two suction fittings 53a (see Fig. 5) the

mutual distance of which corresponds to the width of the sack to be treated. The pipe 53 has a fitting 54 (Fig. 1) from which a hose leads to a suction pump 56 mounted on the frame and driven in any suitable manner, for example by the arm 32. 70

The bell crank lever 52 together with the suction pipe 53 are adapted to oscillate up and down by means of a pull rod 57 (Fig. 1) rotatably connected to an arm 58 having a roller 59. 75

The lower end of arm 58 is pivoted in a bearing 60 on the frame. The roller bears against and is moved up and down by an eccentric cam 61 on shaft 37. 80

A clamping device for holding the inverted sack or bag is provided centrally on a cross bar 62 on the frame 1 and below the shaft 8 carrying the turn-over buck 2. 85

Said clamping device which is illustrated in Fig. 4, comprises an arm 63 pivoted at its lower end in a bearing in the frame, while the upper end of said arm forms the one jaw 64 of the clamping device. The arm 63 carries a double-armed lever 65, 66 the one arm 66 of which forms the other jaw of the clamping device. The arm 65 has a stop 67. The lever 65, 66 is pivotable around a pin 65a in the arm 63 and a spring located in a housing 68 tends to press the jaw 66 against the jaw 64. The arm 63 also carries a movable arm 69 provided at its top with a shoulder 70 corresponding in shape to the stop 67 on the arm 65. Arm 69 carries a fixed releasing arm 69a. To the frame there is mounted a fixed tensioning arm 71 having a roller 72 at its top end. The upper end of a bell crank lever 73, 73a (Fig. 1) rotatable in a bearing 74 on the frame is connected by a pull rod 75 to the arm 63 and the lower arm 73 of said lever is connected by a rod 76 to the arm 41 so that when the latter is being moved (towards the left in Fig. 1) the pull rod 75 and thus the arm 63 will be moved downwards. 95

A spring 77 is provided between the tensioning arm 71 and the upper arm 73a of the bell crank lever which spring tends to raise said arm 73a and thus the rod 75 and the arm 63. The rod 76 is slidable in a rotatable bearing 78 on the arm 41 and has a shoulder 78a which will on the arm 41 returning (towards the left in Fig. 1) with the slide 40 abut against the bearing 78 and will thereby by way of the rod 76 force downwards the upper arm of the bell crank lever 73 together with the pull rod 75 and the arm 63 causing that the arm 65 of the lever 65, 66 mounted on arm 63 is forced upwards with the result that the stop 67 engages the shoulder 70 thus holding the jaw 66 in its open position. 105

Two arms 80 (Fig. 2) actuated by springs 79 pivotable at their front end in bearings 81 are mounted at the top internally on the longitudinal girts of the frame. The arms 80 are in reality double-armed levers the short- 110

er arms of which are cut away on the lower half part and which lie in the path of the rollers 47a on the grippers 46 which rollers are movable together with the slide 40. Consequently, the roller 47a will during the forward movement (to the right in Fig. 2) of the slide 40 slide along the internal faces of the arms 80. On the roller 47a reaching the cut away portion of the shorter arm of the arm 80 it will slip onto the external face of the arm 80 and will during the returning movement of the slide 40 pass along the external face of the spring actuated arm 80.

82 is a collecting table for the sacks or bags to be inverted by the machine.

A lower suction pipe 83 is mounted under the collecting table 82 and immediately below the upper suction pipe 53. The two suction fittings 84 (Fig. 5) of said lower suction pipe 83 are disposed immediately below the suction fittings 53a of the suction pipe 53 and extend upwards through openings in the collecting table to the level of the top face of the latter. The lower suction pipe 83 communicates through a hose with the air pump 56.

The mode of operation of the machine is as follows with reference to Figs. 6 to 10:

At the commencement of the operation the sack or bag 90 to be inverted is placed on the table 82 its open end under the upper suction pipe 53. The latter is now lowered down to the sack due to the actuation of the lever 52. The suction pump 56 is placed in such a manner relatively to its driving member that the suction will commence just at that moment. During the movement of the lever 52 the upper suction pipe 53 will raise the side of the sack next thereto while the other side of the sack is held against the collecting table due to the suction from the lower suction pipe 83. Consequently, the mouth of the sack will be opened, Fig. 6.

The conditions are so that the slide 40 (Fig. 2) will simultaneously be moved up along the guides 39 under the influence of rod 41. The rollers 47a on the grippers 46 will during the said movement of the slide 40 slide along the arms 80 causing the grippers to be forced inwards against the action of the springs in the housings 48. The conditions are further so that the grippers will slide into the opened sack. In the moment the rollers 47a move onto the external face of the arms 80 the grippers 46 will catch hold of the sack so as to stretch its mouth and at the same time hold the sack fixedly which has until now been held by the suction pipes.

Due to the action of its drive members the turn-over buck 2 has been swung upwards and now assumes the position shown in Fig. 6 in which its free end registers with the mouth of the open sack. The slide 40 carrying the grippers 46 now moves downwards 65 the guides 39 and the grippers will conse-

quently pull the sack 90 on to the turn-over buck 2 (Fig. 7). Immediately hereafter the free end of the turn-over buck will be lowered to the position shown in Fig. 8 so that the bottom of the sack drawn on to the turn-over buck will be in front of the turn-over fork 19 (Fig. 8).

The turn-over buck is now by its slide 21 moved against the bottom of the sack and will force said bottom through the opening in the end of the turn-over buck. During the said movement of the turn-over fork 19 the rollers 30 will force the rods 27 inwards so that the rollers 28 of the latter will rest in the semi-circular recess 29 in the cross piece 23. The turn-over fork is therefore allowed to freely pass through the opening in the turn-over buck and as formed by the cross piece of the frame 3, the side plates 4 and the bridge 5.

The turn-over fork will thus force the bottom of the sack into said opening. As the sack is in the manner described pulled off the turn-over buck it will be passed, the outside out, onto the turn-over fork (Fig. 9). Due to the pressure exerted by the turn-over fork 85 against the bottom of the sack the sack will be freed from the spring actuated grippers 46.

While the turn-over fork performs the said inverting operation on the sack the rods 27, which due to their S-shape are no longer under the action of the rollers 30, will swing outwards and will maintain the sack stretched during the inverting operation.

On the slide 40 returning (towards the left in Fig. 1) the bearing 78 on arm 41 will exert a pressure on the shoulder of rod 76 and the latter will then by way of the lever 73 and the pull rod 75 move the arm 63 downwards. The roller 72 of arm 71 will thereby press against the arm 65 of lever 65, 66 and will force the said arm upwards so that the stop 67 on arm 65 will engage the shoulder 70 on arm 69 and will thus be held against the action of the spring in the housing 68. The clamping device is now open.

The conditions are so that the said opening operation of the clamping device will take place prior to the turn-over fork 19 having completed the inverting operation. At the end of said operation the cross piece 23 on the turn-over fork will abut against the releasing arm 69a of the clamping device. The arm 69 will thereby be forced away from the arm 65 and the stop 67 of the latter will be released from the shoulder 70 so that the jaw 66 will due to the action of the spring in the housing 68 smack against the jaw 64. The clamping device is thus clamping around the bottom of the sack passed onto the turn-over fork 19 by the jaws 64 and 66 catching around the sack in the recess 24 of the cross piece 23 of the turn-over fork.

Simultaneously with the turn-over fork 19 finishing the inverting of the sack the free end of the turn-over buck will be raised, the

stem 20 of the turn-over fork passing through the resilient flap 6 (Fig. 3) in the bridge 5 of the turn-over buck.

The turn-over fork will now be returned 6 (towards the right in Fig. 1) by its slide 21, while the clamping device will retain the sack inverted over and now pulled off the turn-over fork (Fig. 10).

The inverting operation proper has now 10 been completed and there only remains to open the jaws so that the inverted sack with its outside out can be released and drop down into a suitable collector.

The clamping device is as described above 15 opened during the return movement of the slide 40 the treatment of the next to follow sack having already commenced, as described above, simultaneously with the inverting operation of the first sack having been completed.

We claim.

1. In a sack inverting machine, a turn-over buck and a turn-over fork coacting with said buck to invert a sack drawn over said buck, a movable gripper device operable to draw a sack over said buck, and suction means arranged to coact with the edges of the mouth of a sack to open the latter and permit introduction of the gripper device 30 therein.

2. In a sack inverting machine, a turn-over buck and a turn-over fork coacting with said buck to invert a sack drawn over said buck, a movable gripper device operable to draw a sack over said buck, and suction means arranged to coact with the edges of the mouth of a sack to open the latter and permit introduction of the gripper device therein, said suction means including upper and lower 40 suction pipes movable apart to open the sack mouth.

3. In a sack inverting machine, a turn-over buck and a turn-over fork coacting with said buck to invert a sack drawn over said buck, a movable gripper device operable to draw a sack over said buck, and suction means arranged to coact with the edges of the mouth of a sack to open the latter and permit introduction of the gripper device therein, said suction means including upper and lower 50 suction pipes, and means for moving said pipes apart to open the sack mouth.

4. In a sack inverting machine, a turn-over buck and a turn-over fork coacting with said buck to invert a sack drawn over said buck, a movable gripper device operable to draw a sack over said buck, and suction means arranged to coact with the edges of the mouth 60 of a sack to open the latter and permit introduction of the gripper device therein, said suction means including upper and lower suction pipes, means to create suction in said pipes while the latter are arranged at the 65 edges of the mouth of a flat sack, and actu-

ating means to subsequently separate said pipes to open the sack mouth.

In testimony whereof we affix our signatures.

JOHANNES KRISTIAN FOLKER.
